DESIGN FOR A MOLDED GLASS ALPHABET FOR FORMING MONOGRAMS OR THE LIKE

Michael Chernow, Brooklyn, N. Y.

Application October 6, 1933, Serial No. 49,411

Term of patent 3½ years

To all whom it may concern:

Be it known that I, MICHAEL CHERNOW, a citizen of the United States and residing at Brooklyn, in the county of Kings and State of New York, have invented a new, original, and ornamental Design for a Molded Glass Alphabet for Forming Monograms or the like, of which the following is a specification, reference being had to the accompanying drawing, forming part hereof, and in which

Fig. 1 is a plan view of a molded glass alphabet for forming monograms or the like, showing my new design,

Fig. 2 is a sectional view on the line 2—2 of Fig. 1, and

Fig. 3 is an edge view on the line 3—3 of Fig. 1.

The individual characters comprise centrally bulging molded glass blocks with faceted bevelled top and bottom edges and with its remaining edges bevelled and unfaceted.

I claim:

The ornamental design for a molded glass alphabet for forming monograms or the like, substantially as shown and described.

MICHAEL CHERNOW.
